UNITED STATES PATENT OFFICE.

JULIUS AUGUST FRIEDRICH REINECKE, OF DRESDEN, GERMANY, ASSIGNOR TO
THE AMERICAN TOBACCO COMPANY, OF NEW YORK, N. Y., A CORPORATION
OF NEW JERSEY.

MACHINE FOR FORMING CIGARETTES WITH MOUTHPIECES.

No. 893,098.

Specification of Letters Patent.

Patented July 14, 1908.

Application filed November 4, 1902. Serial No. 130,025.

To all whom it may concern:

Be it known that I, JULIUS AUGUST FRIEDRICH REINECKE, a subject of the Emperor of Germany, residing at Dresden, Kingdom of Saxony, German Empire, have invented certain new and useful Improvements in Machines for Forming Cigarettes with Mouth-pieces, fully described and represented in the following specification and the accompanying drawings, forming a part of the same.

This invention relates to certain improvements in machines for forming cigarette tubes with mouth-pieces.

In the manufacture of high-grade cigarettes with mouth-pieces, it is desirable to so position the mouth-piece with respect to the cigarette tube that the seam of the mouth-piece will correspond with the seam of the tube. As such cigarettes are usually constructed the mouth-piece is formed from a piece of stout paper spirally coiled, said mouth-piece being inserted into the tube and held in position by the resiliency of the paper. When the cigarettes are constructed in this manner, it is desirable that the edge of the lap which forms the outer coil of the mouth-piece underlie the seam in the cigarette tube formed by joining the overlapping edges of the paper, so that the cigarette presents apparently only a single seam from end to end. In one type of machines employed for making cigarette tubes, the tube, as it emerges from a continuous tube forming mechanism, is cut into lengths which are allowed to drop onto a table and are thereafter rolled across the table to the mouth-piece inserting devices. With this construction there is no certainty that the seam in the tube will be in alinement with the seam of the mouth-piece as it is inserted in the tube. It has been proposed to bring the mouth-piece joint into proper alinement with the seam in the cigarette tube by employing a carrier which transports lengths of tubes from a tube forming mechanism to a mouth-piece inserting mechanism, the tube length being seized after the carrier has brought it into position opposite the mouth-piece inserting devices and rotated so that the seam of the tube is in alinement with the joint or seam in the mouth-piece. This construction requires separate agencies for rotating the tube and is objectionable in other respects.

It is one of the objects of this invention to produce a simple and inexpensive mechanism by which the positions of the cigarette tube or mouth-piece, or both, may be controlled during the movement by which they are brought into assembling position, so that the seam in the tube will be in proper alinement with the joint or seam in the mouth-piece.

A further object of the invention is to improve the mechanism of machines for forming cigarette tubes with mouth-pieces, so that the same may be more certain in operation whereby better results are obtained.

With these and other objects in view, the invention consists in certain constructions and in certain parts, improvements and combinations as will be hereinafter fully described and then specifically pointed out in the claims hereunto appended.

In the accompanying drawings—Figure 1 is a plan view of so much of a machine for forming cigarette tubes with mouth-pieces as is necessary for an understanding of the invention. Fig. 2 is an end view, the position of the observer being indicated by the arrow in Fig. 1. Fig. 3 is a detail elevation, partly in section, illustrating the construction of the tube support and of certain parts of the mechanism connected with the mouth-piece inserting devices. Fig. 4 is an elevation of the devices illustrated in Fig. 3, but showing the parts in different positions. Figs. 5, 6 and 7 are detail sectional views. Figs. 8 and 9 are elevations of the cutting mechanism, the parts being shown in different positions in the two views. Fig. 10 is a section on the line 10, 10 of Fig. 8. Fig. 11 is a section on the line 11—11 of Fig. 8. Fig. 12 is a detail view, on an enlarged scale, of the mouth-piece forming spindle and inserting tube. Fig. 13 is an elevation, partly in section, of a completed cigarette tube.

Referring to the drawings, which illustrate one concrete embodiment of the invention, 1 indicates the table of a machine for forming cigarette tubes with mouth-pieces, the machine being in many of its features of a well-known type. The machine is constructed to form a continuous tube from which the tube lengths for forming the cigarettes are cut, the strip of paper from which the tube is formed being indicated at 2. The strip of paper is bent up into tube form about a man-

drel by means of guides 3, 4 which may be of any preferred form, and which will usually operate to interlock the meeting edges of the tube after which the seam is completed by 5 means of a seaming wheel 5 of ordinary construction, said wheel being mounted on a shaft 6 and driven by a train of gears from any of the shafts of the machine. As the tube passes off the mandrel it is cut into 10 lengths by means of a cutting mechanism which may be of any desired description. Preferably, however, this cutting mechanism will consist of a pair of shears which may be mounted in any desired manner. As 15 shown, the shears consist of a pair of blades 7 which are pivoted at 8 to an overhanging bracket 9 which is provided with a perforated arm 10 through which the tube passes and by which it is guided and supported. 20 The tails of the shear blades are connected by a pull-spring 11, clearly indicated in Fig. 8, and the shears are forced open by means of a sliding block 12 provided with a pair of friction rollers 13. As shown, this block consists 25 of two plates held together by screws 14 passing through a slot 15 in the arm of the overhanging bracket 9. As shown, the block 12 carries a pin 16 which is in the path of the outer end of a pivoted lever 17, said lever being operated by means of a vertical rod 18 which is pinned to the lever. As the rod reciprocates vertically the lever 17 is raised and lowered. On the upward movement of 30 the outer end of the lever the spring 11 draws together the tails of the shears and these tails acting as cams operate in connection with the rollers 13 to move the block 12 vertically. On the downward movement of the outer end of the lever, the pin 16 is struck thereby and 35 forces the block down, opening the shears against the tension of the spring.

The movements of the rod 18 may be effected in any desired manner. As shown, the rod passes through a perforation in the standard of the overhanging arm and is threaded at its lower end, said lower end being provided with two adjusting nuts 20, one located above and one below a slotted lever 21 which is pivoted at 21' to an arm 22. This arm 22 is connected to a slide rod 22' moving in bearings on the under side of the bed of the machine. The lever 21 rests on a rotating cam 23 mounted on a shaft 23' which is located under the bed and driven in any suitable 55 manner.

In order to prevent the tube from buckling, as it would do were the shears stationary, they are given a slight movement in the direction in which the tube is moving during 60 the cutting operation. This movement may be effected by any desired means. As shown, the outer end of the rod 22' is provided with a split collar 25 which embraces a bearing 26 formed on or suitably connected 65 to the lower end of the overhanging arm 9.

The arm 22 before referred to is rigidly connected to the rod 22' and is provided with a cam roller 26 which bears against the surface of a cam 27 mounted on a shaft 28 suitably supported on the bed and driven from any 70 one of the moving shafts of the machine. The outer end of the rod 22' is provided with a bracket 29 to which is connected a spring 30, said spring being at its other end connected to a post 31 depending from the machine table. A guide pin 32 carried on the bracket 29 and engaging in a perforation in a bracket 33 secured to the under side of the table insures that the rod move truly in its bearings. As the cam 27 rotates, the shears 80 are given a forward movement, which movement takes place during the cutting off of the tube length.

The machine is provided with means for bringing a tube length, and a mouth-piece 85 formed by mechanism hereinafter to be described, into position where the two may be assembled, and, in the preferred form of the construction, these means will be so arranged as to control the movement of either the 90 mouth-piece or the tube, or both, so that when they are in assembling position, their seams will be in alinement. In the construction shown, this result is effected by employing a tube carrier which receives the tube 95 with the seam in a given position and transfers it to the mouth-piece inserting mechanism to be hereinafter described, the tube when it arrives in assembling position having the seam in alinement with the joint or seam 100 in the mouth-piece.

The tube carrier may be varied widely in its details of construction. Preferably, however, it will be provided with a plurality of interior supports, that is to say, supports 105 which engage the interior of the tube lengths. As shown, there is provided a hub 34 mounted on or secured to a shaft 35 mounted in a bearing 36 extending upward from the machine table. This hub is provided with a series of longitudinal perforations 37, six being shown, although any desired number of perforations may be employed. The outer shell of the hub is slotted, as indicated at 38 (see Fig. 3), and located in the perforations are 110 supporting pins 39 preferably having conical ends, so that they may readily pass into the cigarette tube lengths, and being provided with stop collars 40. While the pins might be rigid in the carrier they are, in the present 115 machine, given a longitudinal movement to bring them into position to receive the tubes. To this end the pins are provided with projections 41 which engage an interior cam-groove 42 in a stationary cam ring 43, said 120 ring being preferably constructed in two or more parts and being secured by screws, or in any other suitable manner, to the bearing 36.

The shaft 35 is preferably given a step by 130

step movement, this movement being effected by any desired construction. As shown, this shaft is provided with a disk 44 having six pins 45, said pins being arranged to be engaged by a long pawl 46. This pawl 46, as shown, is mounted on a sliding block or carriage 47 moving in a way 48 formed on a block 49 suitably secured to the machine table. The carriage is connected by means 5 of a rod 50 to a crank 51 mounted on a rotating shaft 52 which will be hereinafter referred to. As the shaft 52 rotates, the carriage or block 47 and the pawl 46 will be given reciprocating movements, and on each 10 forward movement the pawl takes over one of the pins 45, so that, on the rearward movement of the pawl, the shaft 35 is advanced one step. The distance of arc through which the shaft 35 and the tube support is moved 15 by the pawl is so calculated that the seam or joint in the tube will be brought, as the support stops, into alinement with the seam or joint in the mouth-piece which is formed by a mechanism which will be hereinafter 20 described.

In order to prevent overrunning, the shaft 35 is preferably provided with a friction disk 53 engaged by a friction strap 54 of ordinary construction. The interior cam groove 42 is 25 so arranged that the tube supporting pins are fully protruded at the time when they are opposite the advancing tube and the support is so located that the conical point of each pin will be engaged by the forward end 30 of the tube just prior to the time when the tube is to be cut off. This position is clearly indicated in Fig. 1. The forward movement 35 of the shears before referred to, therefore, is utilized to push the tube lengths onto the 40 pins and seat them against the stop collars 40.

It may happen that the upper portion of the tube will be deformed slightly by the operation of the shears. A device is accordingly preferably provided for restoring the 45 tube to its circular form before it reaches the mouth-piece presenting means. The device for thus reshaping the deformed tube may be widely varied in construction. As shown, there is provided a light spring 55 (see Fig. 3) 50 formed from a piece of wire, said spring being mounted on a supporting bracket 55'. The end of this spring wire is so located in the path of the tube supports or the tubes carried thereby that the end of the spring 55 will be struck by the tube about in line with the major diameter of the ellipse produced 55 by the deforming action of the shears (see Fig. 8). The light blow on the paper produced by the tube striking the end of the 60 spring will be sufficient to cause the tube to resume its circular form.

The mouth-piece forming mechanism may be of any suitable construction. As shown this mechanism is as to its general features 65 similar to a well-known type of machines and

includes a rotating spindle 56 to which a strip of mouth-piece paper is fed by means of feed rolls 57, the proper lengths of paper to form mouth-pieces being cut off by cutters 58, a striker 59 being provided, as in the machines referred to, to dispose of improperly fed blanks. The spindle 56 is hollow (see Fig. 12) and is provided with a gripper rod 60. The spindle is provided with a slit 61 into which the forward edge of the mouth-piece blank is inserted. As is common in this type of machines, after the forward edge of the mouth-piece blank is inserted in the slit in the winding spindle, the gripper rod is given a slight movement to nip the edge of the blank between it and the interior of the spindle, after which the spindle and rod rotate together to coil the paper into a mouth-piece. The driving means for the spindle and gripper rod have been omitted, as they are well-known in the art, and are, furthermore, unnecessary to an understanding of the present invention.

The machine is provided with a mouth-piece carrier which may be of any suitable 90 construction. In the present machine this carrier consists of a slit tube 62 having a beveled end, this tube in the present construction being also used as a former to coöperate with the winding spindle in coiling the blank 95 which forms the mouth-piece. In the construction shown, this tube 62 is mounted in a bearing 63 which is connected to a block 64. In a bearing 65 which is located above the block 64, but disconnected therefrom, there 100 is a sleeve 66 which is connected by means of a set-screw 67, or in any other suitable manner, to the winding spindle 56. This block 105 and the bearings referred to are clearly shown in Fig. 5, the spindle 56 being shown as having a mouth-piece M coiled about it. The block 64 is held in position between a pair of guides 68 which serve to support the bearing 65 before referred to. The block 64 is mounted on a slide 69 which rests on the machine table, the connection between the block 64 and the slide 69 being effected by means of a pin 70, or in any other suitable manner. The slide 69 (see Figs. 3 and 5) has depending from it a bracket 71 which is adjustably 110 secured to the slide by means of a set screw 72, or in any other suitable manner. To the lower end of this bracket 71 is secured a connecting rod 73, the other end of the rod 73 being secured to a crank stud on a crank disk 115 74 mounted on the shaft 23 before referred to. The crank disk and connections serve to give the slide, the spindle, the mouth-piece carrier 62, the bearing 63 and the block 64 reciprocating movements by which the mouth-piece 120 carrier 62 is caused to enter and retreat from the tube lengths which are presented to the mouth-piece carrier by the pins on the tube support.

When the mouth-piece blank has been 130

coiled by the spindle, the spindle is brought to an abrupt stop, the stopping point determining the position of the seam or outer edge of the outer lap of the coil. It has been found in practice, however, that although the spindle is brought to an abrupt stop, there is a slight tendency, under some circumstances, for the mouth-piece blank to expand like a spring and through this expansion to roll around in the transferring tube, so that the seam or joint formed by the outer edge of the lap will not always come in the same position. Means are accordingly preferably provided to prevent this tendency of the mouth-piece paper to expand. While these means may be widely varied in form, in the preferred construction, one of the lips of the opening in the mouth-piece carrier 62 is provided with a bend or projection 75 which extends into the interior space of the carrier, thus forming a friction surface which exercises a restraining influence on the end of the blank, and overcomes the tendency of the mouth-piece to roll around and expand when the winding spindle is brought to a stop. The position of this projection 75 and its operation on the mouth-piece blank is clearly shown in Fig. 12.

The forward movement of the slide 69 which causes the mouth-piece carrier 62 to enter the tube, of course causes the mouth-piece carrier to leave the winding spindle 56, and means are accordingly provided to strip the mouth-piece from the spindle. In the construction shown there is employed for this purpose a stripping pawl 76 which is pivoted in the block 64, the pawl being held up in position so that its point is behind the mouth-piece carrier by means of a spring 77 and a pin 78. As the block 64 moves forward, the mouth-piece which is on the winding spindle will be pushed off the spindle and remain in the mouth-piece carrier. After the mouth-piece carrier has entered the open end of the cigarette tube and has positioned the mouth-piece in the tube, the mouth-piece will be stripped from the carrier on the return movement thereof so as to leave the mouth-piece in the tube. This is accomplished by means of a spring pressed pawl 79 (see Fig. 1) the point of which enters the slit in the mouth-piece carrier 62, the pawl being so positioned that it will spring in behind the mouth-piece in the mouth-piece carrier when the mouth-piece carrier in its forward movement carries the mouth-piece beyond the end of the pawl. On the return movement of the carrier, the mouth-piece is stripped from it therefore by this pawl. After each tube has received its mouth-piece, it is removed from the supporting pin on the carrier. This removal of the tube lengths may be effected in any desired manner. As shown, the bearing 63 has secured to its top (see Figs. 3 and 4) a spring 80 which

carries a friction pad 81, the pad being located directly over the mouth-piece carrier 62. The bracket 55' which carries the reshaping wire 55 and which is mounted on a standard 82 rising from the bed plate, carries an operating member which, as shown, comprises a pivoted plate 83 pivoted at 84 to an upward extension of the bracket. Normally this plate is held back against a stop pin 85 (see Figs. 3 and 4) by means of a spring 86. The lower end of this plate is in the path of the forward end of the pad carrying spring 80. As the mouth-piece carrier is moved forward by the mechanism before described, the plate is turned on its pivot, as indicated in Fig. 3, allowing the pad carrying spring to pass underneath it. When, however, the mouth-piece carrier has reached the extreme end of its forward movement, the pad carrying spring is advanced so far beneath the plate as to allow it to swing down behind it, as clearly indicated in Fig. 4. When the mouth-piece carrier retreats, therefore, the pad carrying spring is forced downward and the pad presses the cigarette tube 90 length against the outside of the mouth-piece carrier, thus clamping it thereto. This clamping action continues until the tube is drawn off the supporting pin, by which time the pad carrying spring has moved up from beneath the plate 83, so that the spring can rise and release the tube. It is at this time that the spring pawl 79 comes into operation and strips the tube and mouth-piece from the mouth-piece carrier.

After the tube with its inserted mouth-piece is removed from the mouth-piece carrier, it is, or may be, delivered to the re-rolling mechanism, such as is common in this type of machines. This re-rolling mechanism, in the construction shown, comprises a cylinder 87 mounted on the shaft 52, said cylinder coöperating with a curved block 88. The cylinder 87 has connected to it a gear wheel 89 which is driven by a train of gears 110 which includes a gear 90 on the feed roll 57 and a gear 91 on a countershaft 92. The gearing by which this countershaft is driven from the main shaft 93 of the machine is of ordinary character, and since it has no particular bearing on the invention, it is unnecessary to particularly describe it.

A guide 94 of sheet metal or other similar material is, or may be, employed to direct the tube lengths from the mouth-piece inserting mechanism to the re-rolling mechanism. The tube lengths may, if desired, be allowed to drop by gravity from the mouth-piece carrier down the guide 94, or, if desired, means may be employed to assist in their delivery. As shown, there is provided a carrier 95 consisting of a lever which is pivoted to one of the guides 68, said lever being thrown up into position by means of a spring 96. The lever 95 is slotted at 97 and through this 130

slot extends a guide pin 98. The forward end of this lever 95 is provided with a light bow-spring 99 which is so positioned as to operate upon the tube as the same is delivered from the carrier. The slide 64 is provided with a cam roll 100 and the upper side of the lever 95 is provided with a cam surface 101. As the slide 64 moves forward, therefore, the cam roll 100 co-operating with the cam surface 101, pushes the lever 95 down into the position shown in Fig. 4, so that the spring will not interfere with the insertion of the mouth-piece carrier into the tube. On the backward movement of the slide 64, the lever 95 is allowed to rise and its spring operating on the tube accelerates its movement as it is delivered from the carrier.

While the mechanism which has been described embodies a preferred form of the invention changes and variations may be made therein without departing from the invention. It is also to be understood that certain parts of the construction embodying the invention are capable of use independent of other parts. The invention is not, therefore, to be restricted to the specific mechanism hereinbefore described.

What is claimed is:—

1. In a machine for forming cigarette tubes with mouth pieces, the combination with a mouth piece presenting means, of a tube carrier arranged to receive the formed tubes in a predetermined position, means for moving one of said parts to bring the tubes while in such position into alinement with the mouth piece presenting means and devices for assembling the mouth pieces and tubes, substantially as described.

2. In a machine for forming cigarette tubes with mouth pieces, the combination with mouth piece presenting means, of a tube carrier arranged to receive the formed tubes in predetermined position, and means for moving the carrier to bring the tubes while in such position into alinement with the mouth piece presenting means and devices for assembling the mouth pieces and tubes, substantially as described.

3. In a machine for forming cigarette tubes with mouth pieces, the combination with the mouth piece presenting means, of a rotating tube carrier arranged to receive the formed tubes in a predetermined position, means for rotating the carrier with the tubes in such position whereby the tubes are brought into position to receive the mouth pieces, and devices for assembling the mouth pieces and tubes, substantially as described.

4. In a machine for forming cigarette tubes with mouth pieces, the combination with mouth piece presenting means, of a rotating tube carrier provided with a plurality of tube supports, arranged to receive the tubes in a predetermined position, means for rotating the carrier with the tubes in such

position whereby the tubes are brought into position to receive the mouth pieces, and devices for assembling the mouth pieces and tubes, substantially as described.

5. In a machine for forming cigarette tubes with mouth-pieces, the combination with mechanism for forming a continuous tube, of a tube carrier having a plurality of interior tube supports, means for cutting off and placing tube lengths on the supports, and means for operating the carrier, substantially as described.

6. In a machine for forming cigarette tubes with mouth-pieces, the combination with mechanism for forming a continuous tube, of a tube carrier having a plurality of interior tube supports, means for cutting off and placing tube lengths on the supports, mouth-piece presenting means, means for operating the carrier to position the tube supports so that the tubes may receive the mouth-pieces, and assembling devices, substantially as described.

7. In a machine for forming cigarette tubes with mouth-pieces, the combination with mechanism for forming a continuous tube, of a rotating tube carrier having a plurality of interior tube supports, means for cutting off and placing tube lengths on the supports, mouth-piece presenting means, means for rotating the carrier to position the tube supports so that the tubes may receive the mouth-pieces, and assembling devices, substantially as described.

8. In a machine for forming cigarette tubes with mouth-pieces, the combination with mechanism for forming a continuous tube, of a rotating tube carrier having a plurality of interior tube supports, means for cutting off and placing tube lengths on the supports, mouth-piece presenting means, means for rotating the carrier to bring the tube supports into position opposite the mouth-piece presenting means with the seams of the tubes in alinement with the seams of the mouth-pieces, and assembling devices, substantially as described.

9. In a machine for forming cigarette tubes with mouth-pieces, the combination with mechanism for forming a continuous tube, of a rotating carrier provided with a plurality of interior tube supports, means for cutting off and placing lengths of tube on said supports, means for rotating the carrier, and means for giving the tube supports a movement in the direction of their length, substantially as described.

10. In a machine for forming cigarette tubes with mouth-pieces, the combination with mechanism for forming a continuous tube, of a tube carrier provided with a plurality of interior tube supports, means for cutting off and placing tube lengths on said supports, mouth-piece presenting means, means for operating the carrier to bring the supports suc-

- cessively into position opposite the mouth-piece presenting means and with the seams of the tubes in alinement with the seams of the mouth-pieces, means for giving the supports 5 a movement in the direction of their length, and assembling devices, substantially as described.
11. In a machine for forming cigarette tubes with mouth-pieces, the combination 10 with means for forming a continuous tube, of a rotating tube carrier having a plurality of tube supporting pins, tube cutting mechanism, means for operating said mechanism to cut off and seat tube lengths on said pins, 15 mouth-piece presenting means, means for rotating the carrier to bring the pins successively into position opposite the presenting means and with the seams of the tubes in alinement with the seams of the mouth-pieces, and means for inserting the mouth-pieces in the tubes, substantially as described.
12. In a machine for forming cigarette tubes with mouth-pieces, the combination 20 25 with mechanism for forming a continuous tube, of a rotating tube carrier having a plurality of tube supporting pins, a cutting mechanism, means for operating said mechanism to cut off and seat tube lengths on the pins, 30 mouth-piece presenting means, means for giving the carrier step by step movements, said means being constructed to successively bring the pins opposite the mouth-piece presenting means and with the seams of the 35 tubes in alinement with the seams of the mouth-pieces, and means for inserting the mouth-pieces in the tubes, substantially as described.
13. In a machine for forming cigarette tubes with mouth-pieces, the combination 40 45 with mechanism for forming a continuous tube, of a rotating tube carrier having a plurality of tube supporting pins, a cutting mechanism, means for operating said mechanism to cut off and seat tube lengths on the pins, mouth-piece presenting means, means for giving the carrier step by step movements, said means being constructed to successively bring the pins opposite the mouth-piece presenting means and with the seams of the 50 tubes in alinement with the seams of the mouth-pieces, means for giving the pins a movement in the direction of their length, and means for inserting the mouth-pieces in 55 the tubes, substantially as described.
14. The combination with a tube carrier, of means for operating on the tubes in the carrier to restore them to shape when deformed, substantially as described.
- 60 15. The combination with a tube carrier having supporting means for engaging the ends of tubes, and means in the path of the tubes on the carrier for restoring to shape deformed tubes, substantially as described.
- 65 16. The combination with mechanism for forming continuous tubes, of a tube carrier, means including a cutting mechanism for cutting off and placing tube lengths on the carrier, and means in the path of the tubes on the carrier operating to re-shape the tubes 70 deformed by the cutting mechanism, substantially as described.
17. The combination with mechanism for forming continuous tubes, of a tube carrier having a plurality of interior tube supports, 75 a cutting mechanism for cutting off and seating lengths of tubes on said supports, and means in the path of the tubes on the carrier operating to reshape the tubes deformed by the cutting mechanism, substantially as described.
18. The combination with mechanism for forming continuous tubes, of a tube carrier having a plurality of interior tube supports, a cutting mechanism for cutting off and seating lengths of tube on said supports, and a light spring in the path of the tubes on the carrier against which the tube lengths strike whereby tubes deformed by the cutting mechanism are reshaped, substantially as 80 85 90 described.
19. In a machine for forming cigarette tubes with mouth-pieces, the combination with a tube carrier having a plurality of interior tube supports, of mouth-piece presenting means, means for operating the carrier to bring the tubes opposite the presenting means, means for inserting the mouth-pieces in the tubes, and means for removing the tubes from the tube supports, substantially as described.
20. In a machine for forming cigarette tubes with mouth-pieces, the combination with a tube carrier having a plurality of interior tube supports, of means for inserting mouth-pieces in the ends of tubes carried by said supports, and means operating in connection with the mouth-piece inserting means for removing the tubes from the supports, substantially as described.
- 101 11 21. In a machine for forming cigarette tubes with mouth-pieces, the combination with a tube carrier having a plurality of interior tube supports, of a mouth-piece carrier, means for reciprocating the mouth-piece carrier into and out of the open ends of the tubes, means for removing the mouth-pieces supported on the carrier, and means for clamping the tubes to the mouth-piece carrier whereby they are removed from the tube 11 12 supports on the tube carrier, substantially as described.
- 12 13 22. In a machine for forming cigarette tubes with mouth-pieces, the combination with a rotating tube carrier having a plurality of interior tube supports, of a mouth-piece carrier, means for reciprocating said carrier into and out of the open ends of the tubes, a clamp, means for operating the clamp to secure the tubes to the mouth-piece

carrier, and means for removing the mouth-pieces from said carrier, substantially as described.

23. In a machine for forming cigarette tubes with mouth-pieces, the combination with a rotating tube carrier having a plurality of tube supporting pins, of a mouth piece carrier, a spring clamp moving with the mouth-piece carrier, means for reciprocating the mouth-piece carrier into and out of the open ends of the tubes, means for operating the clamp to hold the tubes to the mouth-piece carrier as the same is given its backward movement whereby the tube is moved from the tube supporting pins, and means for removing the mouth-pieces and tubes from the mouth-piece carrier, substantially as described.

24. In a machine for forming cigarette tubes with mouth-pieces, the combination with a mouth-piece winding spindle, of a former coöperating therewith, and means for operating on the mouth-piece in the former to prevent the same from being displaced when the spindle is brought to a stop, substantially as described.

25. In a machine for forming cigarette tubes with mouth-pieces, the combination with a mouth-piece winding spindle, of a forming tube, and a friction surface inside of the tube operating on the mouth-piece paper to prevent the same from being displaced when the spindle is stopped, substantially as described.

26. In a machine for forming cigarette tubes with mouth-pieces, the combination with a mouth-piece winding spindle, of a slitted forming tube in coöperation therewith, and a projection located near the slit and extending into the interior of the tube to bear on the mouth-piece paper to prevent the same from being displaced when the spindle is stopped, substantially as described.

27. In a machine for forming cigarette tubes with mouth-pieces, the combination with a mouth-piece winding spindle, of a slitted forming tube, said tube having one of the edges of the slit bent inward to form a projecting surface which bears on the mouth-piece paper to prevent the same from being displaced when the spindle is stopped, substantially as described.

28. In a machine for forming cigarette tubes with mouth-pieces, the combination with mechanism for forming a continuous tube, of a standard having an overhanging arm, a pair of shear blades mounted on said arm and positioned to cut lengths of tubes from said continuous tube, a spring for closing the shears, a sliding plate for opening the shears, means for operating said sliding plate, a tube carrier and means for reciprocating the standard toward and away from the tube carrier, substantially as described.

29. In a machine for forming cigarette

tubes with mouth-pieces, the combination with a mouth-piece carrier, of tube supporting means, means whereby the mouth piece carrier is caused to enter a tube length to place the mouth-piece therein, means for removing the mouth-piece and tube from the mouth-piece carrier, and means for assisting the delivery of the tube length and its mouth-piece, substantially as described.

30. In a machine for forming cigarette tubes with mouth-pieces, the combination with a mouth-piece carrier, of tube supporting means, means for causing the mouth-piece carrier to enter a tube length to place a mouth-piece therein, means for removing the tube length and its mouth-piece from the mouth-piece carrier, and a spring for assisting in the delivery of the tube length and its mouth-piece, substantially as described.

31. In a machine for forming cigarette tubes with mouth-pieces, the combination with a mouth-piece carrier, of a delivering spring, an operating member for the spring, and means for operating said member to force the spring against a tube which has had a mouth piece inserted therein by the mouth-piece carrier, substantially as described.

32. In a machine for forming cigarette tubes with mouth-pieces, the combination with a rotating tube carrier having a plurality of tube supporting pins, of a mouth-piece carrier, means for reciprocating the mouth-piece carrier into and out of the open ends of the tubes, a spring clamp, means for operating the clamp to hold the tubes to the mouth-piece carrier as the same is given its backward movement, means for removing the mouth-pieces from the mouth-piece carrier, a delivering spring, a carrier therefor, means for operating the carrier to cause the spring to act upon the tubes and mouth-pieces, and a re-rolling mechanism to which the tubes are delivered.

33. In a machine for forming cigarette tubes with mouth-pieces, the combination with a rotating tube carrier having a plurality of tube supporting pins, of a mechanism for forming a continuous tube, a cutter operating to cut off and seat tube lengths on the supporting pins of the carrier, a re-shaping device located in the path of the tubes on the carrier for re-shaping the tubes deformed by the cutter, a mouth-piece carrier, means for reciprocating the carrier into and out of the open ends of the tube lengths, a clamp, means for operating the clamp to hold the tube lengths to the mouth-piece carrier as the same is given its backward movement, mouth-piece removing means, a re-rolling mechanism, and a delivering spring for forcing the tube lengths and their mouth-pieces toward the re-rolling mechanism, substantially as described.

34. In a machine for forming cigarette tubes with mouth-pieces, the combination

with a rotating tube carrier having a plurality of tube supporting pins, of a mechanism for forming a continuous tube, a cutter operating to cut off and seat tube lengths on the supporting pins of the carrier, a re-shaping spring located in the path of the tubes on the carrier for reshaping the tubes deformed by the cutter, a mouth-piece carrier, means for reciprocating the carrier into and out of the open ends of the tube lengths, a spring clamp, means for operating the clamp to hold the tube lengths to the mouth-piece carrier as the same is given its backward movement,

1 mouth-piece removing means, a re-rolling mechanism, and a delivering spring for forcing the tube lengths and their mouth-pieces toward the re-rolling mechanism, substantially as described.

2 In testimony whereof, I have hereunto set my hand, in the presence of two subscribing witnesses.

JULIUS AUGUST FRIEDRICH REINECKE.

Witnesses:

ANTON JANNATSI,
PAUL E. SCHILLING.
